ASSIGNORS TO VICTOR TALKING MACHINE COMPANY, A CORPORATION OF NEW
JERSEY.

CONTAINER FOR TALKING-MACHINE STYLI.

1,350,294.

Specification of Letters Patent. Patented Aug. 24, 1920.

Application filed March 18, 1916, Serial No. 85,058. Renewed June 4, 1920. Serial No. 386,580.

To all whom it may concern:

Be it known that we, HENRY C. BROWN, a citizen of the United States, and a resident of Merion, county of Montgomery, and State of Pennsylvania, and ERNEST JOHN, a subject of the King of Great Britain, and a resident of Ardmore, county of Montgomery, and State of Pennsylvania, have invented certain new and useful Containers for Talking-Machine Styli, of which the following is a specification, reference being had to the accompanying drawing.

Talking machine styli or needles, especially those adapted for use with the gramophone type of talking machine, have heretofore generally been marketed in packages or envelopes, each having a relatively large number of styli loosely contained therein. Styli of this sort are relatively inexpensive, 20 are generally discarded after being once employed in the reproduction of sound, and are frequently purchased in relatively large numbers by the user. Recently, however, another form of talking machine stylus has 25 been placed upon the market which is adapted to be used repeatedly, whereby the reproduction of sound from a very large number of records may be accomplished with the employment of but a single stylus. 30 These styli are relatively much more expensive than the ordinary form of styli heretofore employed and it is therefore desirable to market the same in such manner that each stylus shall reach the consumer 35 in perfect condition and shall so remain until it is desired to use it for the reproduction of sound. Furthermore, as such styli are not generally purchased in quantities, as is the ordinary form of stylus, but 40 only a few at a time, a container or package for their reception may preferably be adapted to hold but a relatively small number of styli.

A principal object of our invention, therefore, is to provide a novel container or package in which talking machine styli may be marketed, which shall serve to keep the styli contained therein free from dust or corrosion and from which, when desired, any of the 50 styli may be readily and selectively removed without in any way disturbing the other styli remaining therein.

Further objects of our invention are to provide a container having the foregoing

characteristics which shall be attractive in 55 appearance, which shall maintain the contained styli securely in position and separated from each other; which will clearly indicate the number of styli contained therein at any time; which may be constructed at a minimum cost, and which shall be well adapted for transportation and commercial handling.

Our invention further includes all of the other various novel objects and features of 60 construction and arrangement hereinafter more definitely specified and described.

In the accompanying drawing, in which is shown a preferred embodiment of our invention, Figure 1 is a front elevation thereof 70 with portions broken away for the sake of clearness and showing a container adapted for the reception of, and containing, four styli, and Fig. 2 is a transverse section taken on the line 2—2 in Fig. 1.

That form of the invention shown comprises a body 1, preferably formed of a flat oblong sheet of cardboard, strawboard, or the like, provided with one or more apertures 2—2 extending completely through the 80 body and preferably located somewhat above the center line thereof, when viewed in the position shown in Fig. 1. These apertures may be of any desired shape, those shown being circular in contour and of a diameter 85 substantially equal to one-half the length of the styli 4 for the reception of which the container is intended, and which of course may be of any suitable form, those illustrated being merely typical, the thickness of 90 the body being also substantially equal to, or a little greater than, the diameter of the shanks of the styli.

Extending radially from each aperture is a slot 5 preferably just wide enough to 95 snugly contain the shank of a stylus, and having its length so proportioned that when the shank of the stylus is positioned therein, as shown, with its end resting against the end of the slot, the point of the stylus will 100 be closely adjacent, but not in contact with, the edge of the aperture diametrically opposite the slot and, in the preferred embodiment of the invention, the slots are arranged to extend downwardly across the center line 105 of the body 1, as shown in the drawing.

On each side of the body, and covering the apertures and the slots therein when the

container is assembled, is positioned a sheet 6, 7 of preferably transparent or translucent material such as oiled paper, maintained in position by a suitable adhesive, each sheet 5 being preferably slightly smaller in size than, but similar in shape to, the body 1. Surrounding both the sheets 6, 7 and the body is located an enveloping cover 9, preferably formed of a single sheet of opaque 10 paper, or the like, in width substantially equal to the length of the body. The length of the cover may preferably be such that when one end 10 thereof is pasted adjacent an edge 11 of the body, the cover may be 15 carried around both sides of the body outside of the transparent sheets 6, 7, and its other end 12 brought down to terminate adjacent the edge 11 of the body, thus completely enveloping both the body and the 20 transparent sheets within the cover, a suitable adhesive being applied to the under side of the cover to secure the same permanently in position. The cover is provided with a pair of openings 14, 15 corresponding 25 to each aperture 2 in the body and arranged to register therewith when the cover is in position, as best shown in Fig. 2, so that in the assembled container the apertures will be entirely uncovered except for 30 the thin sheets of transparent material 6, 7 which lie substantially in the surface planes of the sides of the body, the slots 5 and those portions of the shanks of the styli contained therein being hidden beneath the cover.

It will be understood that the various elements are first cut out by suitable machinery, or otherwise, and thereafter assembled to form the complete container with the 40 styli therein, preferably by first pasting one of the transparent sheets in position on one side of the body, inserting the styli with their shanks in the slots 5 and their points projecting in the apertures 2, pasting the other sheet of transparent material over 45 the other side of the body to cover the styli, and then finally pasting the end 10 of the cover adjacent one of the long edges 11 of the body, and thence carrying the cover completely around the body to terminate adjacent 50 the same edge in such manner that the openings 14, 15 will correctly register with the corresponding apertures 2, sufficient adhesive being applied to the under side of the 55 cover to secure it firmly in position.

It will be evident that after the completion of this operation each stylus will be securely positioned in the container, that portion of each stylus extending in the slot 5 60 being invisible and that portion projecting into the aperture being more or less clearly visible, depending upon the transparency of the sheets 6, 7 by which it is covered. In practice these sheets are preferably made of 65 material sufficiently transparent to permit

the point of the stylus to be readily visible without the necessity of holding the same up to the light.

It will be further evident that the assembled container with the styli positioned 70 therein constitutes a substantially flat package which lends itself readily to transportation and commercial handling and in which the styli are maintained secure from corrosion and other damage indefinitely, and that 75 at any time one or more of the styli may readily be removed from the container by pushing the point of the stylus outwardly through one of the transparent sheets by means of suitable pressure applied against 80 the other sheet conveniently by the thumb or finger, without in any way disturbing any of the other styli in the container, and that after all of the styli have been removed from the container the same may be discarded.

While we have herein illustrated and described a preferred embodiment of our invention with considerable particularity, we do not thereby desire or intend to limit 90 ourselves specifically thereto, as it will be evident that various minor changes may be made in the form and arrangement of the various details of our invention and that the various elements may be assembled 95 in any way desired other than that which we have outlined and that the container may be adapted for the reception of any desired number of styli without departing from the spirit and scope of our invention 100 as defined in the appended claims.

Having thus described our invention, we claim and desire to protect by Letters Patent of the United States:

1. A container for talking machine styli 105 comprising a body having an aperture and a slot communicating therewith, transparent material on each side of said body covering said aperture, and a cover enveloping said body and having openings registering with 110 said aperture, the sides of said slots being adapted to wedge between them the shank of a stylus and to direct the point of a stylus into said aperture.

2. A container for a talking machine 115 stylus comprising a body of thickness substantially equal to the diameter of a stylus and having an aperture and a slot communicating therewith, transparent material covering said aperture, and a cover having 120 an opening in register with said aperture, the sides of said slot being adapted to wedge between them a portion of a talking machine stylus and to direct another portion into said aperture.

3. A container for a talking machine 125 stylus comprising a body having an aperture and a slot adapted to receive the shank of a stylus communicating therewith, a sheet of transparent material secured on each side of 130

- said body and covering said aperture, and a relatively opaque cover surrounding said body and said sheets and having openings adapted to register with said apertures 5 whereby the point of a stylus having its shank positioned in said slot is visible through said sheets.
4. A container for a talking machine stylus comprising a body substantially equal 10 in thickness to the diameter of a stylus and having an aperture and a slot adapted to receive the shank of a stylus communicating therewith, the width of said slot being substantially equal to the thickness of said 15 body, a sheet of transparent material se-
- cured on each side of said body and covering said aperture, and a relatively opaque cover enveloping said body and said sheets and having an opening adapted to register with said aperture whereby any portion of 20 a stylus projecting in said aperture is visible through said sheets and any portion of a stylus in said slot is rendered invisible by said cover.
- In witness whereof we have hereunto set 25 our hands this 16th day of March, A. D., 1916.

HENRY C. BROWN.
ERNEST JOHN.
